UNITED STATES PATENT OFFICE.

THOMAS MANEY, OF LOUISVILLE, KENTUCKY.

GUARD-RAIL FIXTURE FOR RAILWAY TRACKS.

Application filed July 25, 1922. Serial No. 577,397.

To all whom it may concern:

Be it known that I, THOMAS MANEY, a citizen of the United States, residing at Louisville, in the county of Jefferson and State of Kentucky, have invented certain new and useful Improvements in Guard-Rail Fixtures for Railway Tracks, of which the following is a specification.

My invention relates to an improvement in guard rail fasteners and compensating tie-plates for railway tracks.

One of the objects is to provide a fastening in which the manufacture will be simplified, and in fact reduced to a minimum, and this invention presents other advantages over the construction set forth in my application Serial No. 539242, filed Nov. 25, 1921, which will fully appear in the progress of this specification.

20 In the accompanying drawings:

Fig. 1 is a view in transverse section through the rail and guard-rail showing the tie-plate, castings and spikes, in elevation;

25 Fig. 2 is a plan view of the tie-plate.

The numeral 1 represents the plate, and 1' is the usual abutment to receive one edge of the main rail C.

The plate is reduced to a very simple form 30 for rolling, and better carries out the compensating plan. The dotted line represents the surface of the cross-tie, after the plate under the weight of the rolling load has settled to the point where the area bearing 35 upon the tie on the inside (side next the center of track) of the main rail C is sufficient to compensate for the area bearing upon the tie outside of the main rail. This plate is not flat on its bottom surface, as 40 the drawings clearly show. If this plate were flat upon its bottom surface, bearing upon the tie throughout its entire length, it would settle more rapidly on the outside, and this uneven settling would continue and 45 increase, resulting in the canting of the main rail outwardly, which, for many reasons, is very objectionable. But, if the bottom of the plate is shaped as shown, with the initial bearing from zero to X, owing to the pre- 50 ponderance of bearing area outside of main rail C the settling would be more rapid upon the inside of the main rail, and this unequal settling will cease when the bearing area inside is extended to a compensating 55 area. As a result, we have the main rail

slightly canted inwardly, which is desirable, instead of having a more decided cant outwardly, which is very objectionable.

While it is not essential, for obvious reasons I prefer to form a vertical shoulder 60 3 integral with and upstanding from or approximately at the inner edge of the base-plate, as shown in Fig. 1, as this will permit the undulating or vertical wave motion of rails incident to the movement of rolling 65 stock thereover. The guard-rail D to some extent will partake of this movement, and this shoulder 3 permits this, thus avoiding useless strains which might result from the rails being held more rigidly. Furthermore, 70 a plate with a flange of this type is easily rolled.

A toggle casting A is interposed between the inner edges of the base flanges of the main rail C and the guard rail D, and is 75 recessed to receive them as shown in Fig. 1. Casting B is provided with an open jaw 2 to receive the outer base flange of the guard-rail and is provided with a deep vertical recess 12 to receive the vertical shoulder 3 80 of the tie-plate.

The tie-plate is provided with the spike-holes 4, 5, 6 and 7 to receive the spikes 8, 9, 10 and 11, respectively, which latter are preferably of the cut-spike variety.

The special shape of the bottom of the tie-plate constitutes its compensating feature, and is an all-important feature of my present invention.

85 I claim:

1. In a guard-rail fixture for railway tracks, the combination of a base-plate having a vertical shoulder, a main rail, a guard-rail, two castings, one of which is interposed between and fitted to the inner flanges of 90 the two rails, the other fitted to the outer flange of one of said rails and recessed to receive the vertical shoulder of the base-plate, and means for spiking through the base-plate and against said shoulder.

2. A guard-rail fixture for railway tracks including a base-plate, the major portion of the lower surface of which is flat and adapted to rest upon a cross-tie, and the remainder of said lower surface cut away so 100 said portion is initially removed from the tie.

3. A guard-rail fixture for railway tracks including a base-plate, the major portion of the lower surface of which is flat and 110

adapted to rest upon a cross-tie, and the remainder of said lower surface cut away so said portion is initially removed from the tie, and inclined and gradually sloping away 5 from the tie to the end of the base-plate.

4. A guard-rail fixture for railway tracks including a base-plate, the major portion of the lower surface of which is flat and adapted to rest upon a cross-tie, and the remainder of said lower surface cut away so said portion is initially removed from the tie, and inclined and gradually sloping away from 10 the tie to the end of the base-plate, whereby the entire base is in the form of a single obtuse angle.

5. A guard-rail fixture including a base-plate, the major portion of the lower surface of which is constructed initially to rest flat upon the tie, and the remaining portion 20 of which ultimately is forced down in contact with the tie as the surface engaged by the plate becomes worn to receive it.

6. The combination of main and guard-rails, and a base-plate, the major portion 25 of the lower surface of which, and upon which the base of the main rail rests, is approximately straight and flat and rests initially upon the tie, and the lower surface of the remaining portion over which the guard-rail is located extending away from the 30

plane of the major portion of the base-plate.

7. In a guard-rail fixture for railway tracks, a base-plate, the major portion of the lower surface of which is approximately flat and straight, and the remaining portion 35 being inclined to the plane of the lower surface of the major portion, said base-plate provided with a deep vertical shoulder at one edge, in combination with main and guard-rails, a casting inserted between said 40 rails, and a casting having recesses to receive the vertical shoulder and the outer flange of one of the guard-rails respectively.

8. In a guard-rail fixture for railway tracks, a base-plate, the major portion of the 45 lower surface of which is approximately flat and straight, and the remaining portion being inclined to the plane of the lower surface of the major portion, said base-plate provided with a deep vertical shoulder at 50 the edge of the inclined portion, in combination with main and guard-rails, a casting inserted between said rails, a casting having recesses to receive the vertical shoulder and the outer flange of one of the rails respectively, and fastening means for securing the 55 base-rails to the ties.

In testimony whereof I affix my signature.

THOMAS MANEY.
